UNITED STATES PATENT OFFICE.

ERWIN A. GEIGER, OF WYOMING, NEW JERSEY, AND AUGUST F. SCHRAEGLE, OF RIDGEWOOD, AND HENRY T. JENNINGS, OF GLENDALE, NEW YORK, ASSIGNEES TO RAPID ADDRESSING MACHINE COMPANY, A CORPORATION OF NEW YORK.

DETACHABLE PEDAL CONNECTION FOR ADDRESSING MACHINES.

Application filed August 14, 1926. Serial No. 129,135.

This invention relates generally to automatic means for tripping the driving clutch of a power-driven mechanism, and to means under control of the operator for afterwards resetting the same so that the machine may continue in operation until the clutch is again automatically thrown out. More specifically it embodies an improvement on the invention described and claimed in our U. S. Patent No. 1,518,912, granted December 9, 1924, and in certain respects is a modification of the invention described and claimed in our application Serial No. 114,415, filed June 8, 1926. Our invention is herein illustrated in the form in which it has been applied to an addressing machine of the type covered by U. S. Patent No. 1,256,509 granted to E. D. Belknap February 19, 1918.

Our present improvement embodies one device for overcoming the noise and jar created in the operation of certain previously patented apparatus of this general character by inserting a detachable link in the chain of connections from the pedal system (the printing pedal more particularly) to the clutch throw-out mechanism and having the automatic selecting device (not shown) trip this link when one of the predetermined class of cards is fed out of the magazine to printing position, the pedal or pedals remaining locked or held in depressed position until released by the operator, the connection to the clutch being then reestablished. One form of apparatus embodying our present invention is illustrated in the attached four sheets of drawings, in which,

Fig. 1 is a side elevation of the pedal system and part of the automatic mechanism for tripping the main driving clutch, some other portions of the machine being shown broken away in part.

Fig. 2 is a general plan view of the pedal system, parts being shown in section on line 2-2 of Fig. 1, and others broken away.

Fig. 3 is a detail perspective view on a larger scale of portions of the pedal system and clutch tripping mechanism, parts being broken away.

Fig. 4 is a perspective detail view of the reset pedal adjusting sleeve and of the operating portion of the reset pedal sleeve.

Fig. 5 is a detail side elevation of the pedal locking apparatus in operative adjustment

but in the released position assumed when the reset pedal is depressed. 55

Fig. 6 is a similar view showing said lock in engagement.

Fig. 7 is a similar view of said lock in inoperative adjustment in the position occupied while the reset pedal is raised into normal position, and, 60

Fig. 8 is a similar view showing said lock and pedal in the position assumed when said pedal has been depressed to reset the pedal connections. 65

Throughout the drawings like reference characters indicate like parts.

1, 1, are the uprights of the main frame of the machine supporting a table carrying the operating parts such as the card handling, printing and selective mechanism (not shown), said uprights being held together by side bars, shown at 3, and cross bars such as 2 and 23 shown broken away. 10 (Fig. 1) represents diagrammatically a clutch on the main driving shaft of the machine which is usually of the one revolution type, being automatically thrown out at the end of each cycle of operation of the machine by the throw-out cam 72 when the latter is swung up on its pivot 73 by the spring 19 into the position shown in Fig. 1. 17 is a pedal rigidly mounted on the yoke 89, pivoted on the rear cross bar 2 at 18, 18. Said pedal 17 is detachably connected by notched latch link 12, pin 14, lever 98 and link 97, to the throw-out cam 72. 70 75 80 85

This latch 12 is pivoted at its lower end by screw 13 to pedal 17 and has a notch 11 in its front edge which normally engages pin 14 to form the above described train of connecting mechanism from pedal 17 to cam lever 72. The upper end of latch 12 is connected by link 26 to core 27 of solenoid 28. Whenever solenoid 28 is energized by the selective mechanism, which may be of the construction shown in our Patent No. 1,578,912 or of that shown in our pending application Serial No. 114,415, filed June 8, 1926, or of any other type, latch 12 will be pulled to the left 100 (looking at Figs. 1 and 3) and notch 11 will then clear pin 14 as shown in dotted lines in Fig. 1. This will allow spring 19 to lift cam lever 72 and throw out clutch 10 at the end of the current cycle; even though pedal 17 is still held in depressed position. 95 105

If, after the machine has stopped, the operator releases pedal 17, spring 110 will lift it and latch 12 so that notch 11 will be on a level with pin 14, and can reengage it and reestablish the pedal connection to cam 76 if latch 12 is swung back to the right into position shown in full lines in Fig. 1.

The apparatus for thus relatching pedal 17 to the lever 98, here illustrated, comprises the link 26^a, one end of which is pivoted at 15 to the upper portion of latch 12, while its other end is pivoted at 37 to the crank arm 36 on sleeve 35 which is loosely mounted on cross bar 23 of the main frame, which 15 cross bar is of cylindrical shape, said sleeve 35 having operative connections to reset pedal 29, also pivoted on cross bar 23. The preferred form of operating connections between pedal 29 and sleeve 35 comprises a second sleeve 30 to which pedal 29 is rigidly connected by crank arm 21 and which sleeve is also loosely mounted on shaft 23 and provided with a projecting lug 38 cooperating with lug 40 projecting from the adjacent 25 end of sleeve 35. Obviously, when pedal 29 is pressed downward, if lugs 38 and 40 are in contact, the rotation of sleeve 30 will be transmitted to sleeve 35, and link 26^a will be pulled to the right (looking at Fig. 1), thus 30 slightly swinging latch 12 sufficiently to bring it back into the full line position shown in Fig. 1. This will pull out solenoid core 27 into the position shown in Fig. 1, cause the latch to engage pin 14 (assuming that 35 pedal 17 is in raised position), and reset the parts so that when pedal 17 is again depressed the parts will assume the position clearly shown in Fig. 3, the main clutch will be then disengaged and the machine again 40 started into operation.

In a machine organized to run continuously until the selective apparatus or other automatic device trips the latch 12 and stops the machine, it may be desirable to provide means for locking the pedal 17 in depressed position so that the operator need not hold his foot upon it or otherwise positively maintain it in depressed position by continuous effort. In the apparatus described this is 45 accomplished by the following train of mechanism. Swinging lock member 20 is carried by sleeve 30 and adapted to engage a lug 4 on pedal 104, which is pivoted at 105 to pedal yoke 89 and overhangs the laterally projecting stud 106 carried by pedal 17. This pedal 104 (called the skip pedal in machines of this character), when depressed, carries down with it pedal 17, and, thereafter so long as lock 20 is in line with lug 4, will be held by 50 20 in depressed position and also hold down pedal 17, thus permitting the machine to run on. When, however, the operator presses down on reset pedal 29, he will swing lock 20 out of line with lug 4, as shown in full 55 lines in Fig. 1 and thereupon spring 110

(Figs. 1 and 2), which is anchored on projection 111 from one of the uprights 1 of the main frame and at its lower end connected to pedal 17, will raise said pedal 17, lifting latch 12 so that notch 11 will be ready for reengagement with pin 14, which notch is simultaneously swung into such engagement with said pin by the same or continued movement of reset pedal 29, through the train of connecting mechanism terminating in link 75 26^a as before explained. Upward motion of the pedal 17 also carries up skip pedal 104 through the action of stud 106.

Spring 110^a connected at its upper end to the crank arm 39 on sleeve 30, and at its lower end to skip pedal 104, tends to rotate sleeve 30 in a clockwise direction, (looking at Figs. 5 and 6) whenever skip pedal 104 is depressed, with the result that as soon as lug 4 on said pedal gets below the lower end of swinging lock 20, the latter is snapped over into position shown in Fig. 6, so that after the operator removes his foot from pedal 104 it is still held down by lock 20.

Lock 20 is prevented from swinging too far in this resetting operation, and is held in position to register with lug 4, by projection 24 on the upper side of lug 4.

107 is a link pivoted at 25 to skip pedal 104 and operating a card skipping mechanism, not shown, but similar to that described in our before mentioned patent, and in Belknap Patent No. 1,256,509.

Obviously the above described mechanism renders it possible for the operator to proceed on either of the plans explained in said Belknap Patent No. 1,256,509. That is to say if he depresses skip pedal 104 the machine will start and continue to feed and skip cards as long as pedal 104 is held down, and latch 12 engages pin 14. If he depresses pedal 17, the machine feeds and prints from all cards so long as latch 12 is in engagement. Also, if the skip pedal 104 is locked down by swinging arm 20 the operator may temporarily leave the machine while it is so controlled, as was the case with the modified attachment described in our Patent No. 1,518,912. In either case, if a selective attachment is in use the latch 12 will be 110 tripped and the machine stopped whenever a card of the predetermined class comes into printing position, and the operator can then decide whether to print from that card or to skip it, and accordingly depress pedal 17 or 104. If the machine is operating on a set of cards the major portion of which are to be skipped, the pedal 104 will be normally locked down, the printing pedal 17 only occasionally and temporarily depressed to produce one printing cycle, the reset pedal 29 will thereafter be temporarily depressed to reset latch 12, and operations resumed by again locking down pedal 104, and no further adjustments are required.

If, however, the machine is to be run with a lot of cards the major portion of which are to be used in printing and only a few of them skipped, two complications would result with the above described apparatus. The desired result could only be attained by the operator holding down pedal 17 and so running the machine to print until a card to be skipped came along to actuate the selective device. But, as the pedal 104 would then necessarily be in raised position, the pull of magnet 28 could not move the latch 12 because the lug 4 would then be up along side of lock arm 20, and sleeves 30 and 33 could not be oscillated to permit latch 12 to be tripped. Also, if latch 12 could be tripped under these conditions (as by the insertion of an elastic section in link 26^a, for instance), the machine thereby stopped and then pedal 104 temporarily depressed to skip the card then in printing position, (after pedal 17 had been temporarily raised to permit latch 12 to reengage) the before described automatic action of lock 20 would produce a complication in that it would lock the machine in skipping adjustment (the moment pedal 104 was thus depressed) and thus cause it to run on, skipping all cards (which should be printed) until a card which belonged to the class which alone were intended to be thus skipped arrived in printing position, latch 12 thereby tripped, and the machine stopped. After releasing pedals 17 and 104 by depressing pedal 29, and thereby resetting latch 12, depressing pedal 104 to skip that card would reset lock 20 and repeat this series of operations, with the result that all cards (except those run off before the described first actuation of the selective device) would be skipped and none could be used for printing. To avoid both these difficulties it is necessary to shift lock arm 20 temporarily so that it can vibrate without engaging lug 4 when the machine is to be run on the printing plan with only occasional skipping. The preferred means for thus shifting and disabling lock 20 is best shown in Figs. 4 to 8.

Collar 31, which is locked to cross bar 23 by set screw 32, and so serves to prevent sleeve 30 from sliding along said bar away from sleeve 35, has a sector-shaped projection 33 which engages semi-circular jaw 34 on sleeve 30, and thereby also limits the amplitude of oscillation of sleeve 30, and pedal 29, to a degree just sufficiently to give resetting crank 36 the amount of motion needed to cause reengagement of notch latch 12 with pin 14. The locus of oscillation of sleeve 30 needed for this purpose may be shifted by adjusting contact screw 38^a in lug 38. If then screw 38^a is backed off so that lug 38 must move all the way (or nearly all the way) up to lug 40 before reset sleeve 35 begins to be rotated by depression of pedal 29, and some means is provided for preventing pedal 29 (when released) from swinging back into the position shown in Fig. 6, lock arm 20 will never engage lug 4 to lock pedal 104 down, but will oscillate idly from the position shown in Fig. 7 to that shown in Fig. 8. That is to say, the oscillation of pedal 29 needed to oscillate reset sleeve 35 and cause latch 12 to reengage can then be obtained without ever causing lock 20 to register with lug 4. This shift in the locus of operation of pedal 29, lock 20 and sleeve 30 is accomplished by merely loosening set screw 32 and slightly rotating collar 31 on cross bar 23 in a counter-clockwise direction when looking at Fig. 3 (in a clockwise direction when looking at Figs. 4 to 8), and reclamping it in this other position by means of set screw 32. The accurate adjustment of collar 31 in either position is secured by radial pin 43 in cross bar 23 engaging sector slot 42 in said collar. When the pedal system is to be set for automatically skipping cards collar 31 is set as shown in Figs. 5 and 6 with the left hand end of slot 42 against pin 43, and lock 20 then functions, contact screw 38^a in lug 38 protruding as shown in Figs. 3, 5 and 6. When, however, the pedal system is to be set for automatically printing cards (pedal 17 being then normally held down by the operator and pedal 104 being normally held up by spring 110^a), collar 31 is set in the position shown in Figs. 7 and 8 with the right hand end of slot 42 against pin 43. This, by operation of interlocking elements 33, 34, limits the locus of oscillation of pedal 29, lock 20 and sleeve 30 to the positions shown in those figures, and lock 20 then merely moves idly back and forth in the latch resetting operation, never engaging lug 4. To enable this shifted locus of oscillation of lug 38 to have the same effect on reset sleeve 35 as that before described, the contact screw 38^a must be backed off so that lug 38 may more nearly approach lug 40 before reset crank 36 is moved. This last described adjustment is indicated in Figs. 7 and 8.

Preferably trip lever 98 is pivoted on cross bar 23 by sleeve 5 and is forked at the end as shown at 16 to form a guide slot for latch 12. Lock arm 20 is made adjustable in length by its contact button 20^a carried on screw 22. Pedal 76, pivoted at 88 on pedal yoke 89 and having an elbow 90 provided with contact screw 91 for engaging said yoke, operates a repeat printing device such as described in our application Serial No. 114,415. Pedal 76 is normally held up by spring 93. Collar 41, fast on cross bar 23 prevents sleeves 5, 35 and 30 from sliding to the left.

The complete procedure in operating our invention when applied to the machine of the Belknap patent may be briefly stated as

follows: Assuming that the selective device (not shown) has been set to be operated by stencil cards which are to be used in printing, parts are adjusted as shown in Fig. 3 and in full lines in Fig. 6. The operator having pressed down skip pedal 104, which has thereupon been locked down by arm 20, the machine starts off, skipping all cards until one of the class to be printed arrives in printing position. Solenoid 28 is then energized and trips latch 12, releasing stop lever 98 which permits cam 72 to rise and trip clutch 10, and pulling reset crank 36 and lug 40 over into the position shown in dotted lines in Fig. 6. The operator then depresses reset pedal 29, which both swings lock 20 so as to release pedals 104 and 17 so that they can rise and lift latch 12 so that notch 11 will come opposite pin 14, and pulls said latch forward into engagement with said pin, parts assuming the position shown in Fig. 5. If the operator then decides to print with the stencil card lying exposed in printing position, he momentarily depresses pedal 17, causing the machine to perform one printing cycle (as pedal 104 is held up by spring 110^a) and then come to a stop as clutch 10 throws out. Next he depresses pedal 104 again, which is thereupon locked down by 20 (parts resuming the full line positions shown in Fig. 6), and the machine resumes feeding and skipping cards as before. If the operator decides to over-rule the choice made by the selective device he omits depressing pedal 17 and depresses pedal 104 immediately after resetting latch 12 by means of pedal 29 and thereupon the machine starts feeding and skipping again without any intermediate printing operation.

If the selective device has been set for actuation by stencil cards which are to be skipped, parts are adjusted as shown in Fig. 7, thus disabling lock 20, and the operator holds down pedal 17. This starts the machine, and as skip pedal 104 is held up by spring 110^a, the machine prints from all cards fed out until one of the class to be skipped reaches printing position. The selective device then energizes solenoid 28 and latch 12 is tripped, stopping the machine as before. This also pulls lug 40 over against lug 38 as shown in dotted lines in Fig. 7. The operator then releases pedal 17 (which rises) and pushes reset pedal 29 further down into the position shown in Fig. 8. The lost motion between lugs 38 and 40 having previously been taken up, as above explained, this movement of pedal 29 oscillates resetting crank 36 and resets latch 12 on pin 14. Skip pedal 104 is then momentarily depressed to cause the clutch to make one revolution and then throw out, which causes the machine to eject the card without printing from it. Foot pressure is then transferred

to pedal 17 and the machine resumes feeding and printing as before. If, while the machine is in this adjustment, the operator decides at any time to overrule the choice made by the selective device and to print from the card arrested in printing position, instead of skipping it as the classification suggests, he depresses pedal 17 immediately after resetting latch 12, and the machine thereupon prints from that card and from succeeding cards until another one of the class which will actuate the selective device comes into printing position.

If desired, when the reset parts are adjusted as in Figs. 7 and 8, the supply circuit for solenoid 28 may be broken and thereafter the machine operated without automatic selection occurring, the operator merely following the instructions given in the prior Belknap patent, watching the cards as they are fed into printing position and deciding himself, as each comes into view, whether to skip it or to print with it. Skip pedal 29, will, however, have to be depressed after each depression of pedal 104, to free lock 20, or else it must be fixed in depressed position.

The main advantages of this invention over the construction shown in our Patent No. 1,518,912, arise from the fact that the automatic stoppage of the machine by a selective, or other, device is accomplished without allowing the pedal or pedals depressed to rise suddenly, and that the selective device operates effectively whether the machine has been adjusted to normally print with, or skip, the cards fed to it. Also, the pivoting of stop lever 98 on front cross bar 23 and having it extend toward the rear of the machine permits the pedal system to be moved back so the operator can sit close to the machine with his feet under it.

The main distinction, so far as inherent advantages are concerned, between the herein described mechanism and that shown in our copending application Serial No. 119,826, filed June 1, 1926, consists in the wider range of possible adjustments and results above described.

That is to say, with the mechanism described in our said prior application the machine could only be adjusted to run continuously in the skipping phase, any cooperating selective attachment being actuated (and thereby stopping it) when a card which was to be printed came into printing position.

If any attempt had been made to reverse the operation of the apparatus of application No. 119,826, and run it in the printing phase by holding down printing pedal 17 until any cooperating selective device was actuated by a card to be skipped and stopped the machine, it would have been abortive because the raised position of the skip lever

then necessary would have caused its co-operating lug 4 to hold lock arm 20 (and its connected train of elements) in a position which would have prevented the core 5 of the solenoid being pulled in whenever the selective device energized the solenoid (as hereinbefore described with reference to the similar apparatus employed in our present invention) and all selective action would 10 have been nullified, with the result that the machine would have run on, printing from all cards and simply straining the parts (without producing any other effect) every time a card of the class that should be 15 skipped came into printing position. This was so because our said prior application disclosed no means for so adjusting lock arm 20 as to put it out of effective action.

The main distinction between the apparatus of our said prior application and that herein described therefore lies in some means (such as described, or its equivalent) for disabling lock arm 20 and thus permitting the machine to be run in printing phase by 20 holding pedal 17 down without at the same time thus nullifying the action of any co-operating selective device. Another and minor distinction in details of construction arises from the substitution of a different 25 form of detachable trip latch 12, here shown, which totally disconnects pedal 17 from clutch throwout cam member 72 while that described in our said prior application merely permitted a temporary elongation of 30 the link connecting pedal 17 with said clutch throwout 72; the result of the two operations being, however, the same in both cases.

While we have shown and described our invention as applied to an addressing machine of the particular type above referred to, it is evident that modified forms of the invention might be applied to other forms of addressing machines and to other classes of power-driven mechanism whenever it is 40 desirable to automatically stop the same without producing objectionable noise and shock, and this can be done without departing from the underlying principle of our invention as the same has been set forth in 45 certain of the appended claims.

Having described our invention, we claim:

1. The combination, with a power-driven mechanism comprising a main frame and driving means, of a power disconnecting device 50 normally tending to go into action mounted on said frame, a movable element connected to said power disconnecting device and adapted when depressed to hold it out of action, a pedal, a swinging link pivoted to said pedal and having a projecting portion adapted to engage said movable element when swung toward it, and automatic means for occasionally swinging said link away from said movable element, whereby the connection between said movable element and

said pedal is broken and the power automatically cut off while said pedal remains in depressed position.

2. A structure such as defined in claim 1 combined with means under control of the operator for swinging said link back into engagement with said movable element, whereby said power disconnecting device is again put under control of said pedal.

3. A structure such as defined in claim 1 75 combined with a second pedal adapted to swing said link back into engagement with said movable element.

4. A structure such as defined in claim 1 combined with a second pedal pivoted on 80 said frame, and a lost motion connection from said pedal to said link, whereby when said link is swung out of engagement with said movable element said lost motion connection is closed so that when said second 85 pedal is subsequently depressed said link is pulled back into engagement with said movable element.

5. The combination, with power-driven mechanism, of a power disconnecting device 90 normally tending to become operative, a pedal, connections from said pedal to said device normally serving to hold the latter inoperative while said pedal is depressed, a lock for holding said pedal in depressed position, automatic means for breaking said connection while said pedal is depressed, and apparatus under control of the operator for tripping said lock and subsequently restoring said connection when the released pedal 100 rises.

6. A structure such as defined in claim 5 combined with a spring normally tending to lift said pedal.

7. A combination such as defined in claim 5 105 in which said last mentioned apparatus comprises a second pedal operatively connected to said lock and to said first mentioned pedal connections.

8. In a multiple pedal system for controlling the operation of an addressing machine, which said system comprises a printing pedal and a skip pedal, the combination, with said above recited pedal system, of a power disconnecting device normally tending 110 to go into action, a detachable connection from said device to said printing pedal adapted to hold said device out of operation while said printing pedal is depressed, and automatic means for breaking 120 said connection.

9. A structure such as defined in claim 8 combined with means for simultaneously depressing said printing pedal when said skip pedal is depressed but permitting said printing pedal to be depressed without moving said skip pedal.

10. A structure such as defined in claim 8 combined with means for simultaneously depressing said printing pedal when said skip 130

pedal is depressed but permitting said printing pedal to be depressed without moving said skip pedal, a lock for temporarily holding said skip pedal depressed and apparatus associated with said lock for restoring said broken connection to the printing pedal when said skip pedal is released.

11. A structure such as defined in claim 8 combined with means for simultaneously depressing said printing pedal when said skip pedal is depressed but permitting said printing pedal to be depressed without moving said skip pedal, a locking device for holding said skip pedal depressed, a resetting pedal adapted when depressed to trip said locking device, and apparatus actuated by the depression of said resetting pedal to restore said connection between said printing pedal and said power disconnecting device.

12. A structure such as defined in claim 8 combined with means for simultaneously depressing said printing pedal when said skip pedal is depressed but permitting said printing pedal to be depressed without moving said skip pedal, a locking device for holding said skip pedal depressed, a resetting pedal adapted when depressed to trip said locking device, and apparatus actuated by the depression of said resetting pedal to restore said connection between said printing pedal and said power disconnecting device, together with means for temporarily disabling said locking device, whereby said skip pedal may be then depressed without interfering with subsequent control of the machine by said printing pedal.

13. In an apparatus of the character described, the combination of a power disconnecting device, a pedal having a detachable connection to said device, automatic means for breaking said detachable connection, a swinging arm adapted when in one position to engage said pedal and hold it in depressed position, a second pedal rigidly connected to said arm, an adjustable train of mechanism actuated by said second pedal for restoring said detachable connection, and adjustable means for shifting the locus of vibration of said arm and of said second pedal, whereby, when said arm and second pedal are limited to one locus of vibration necessary for restoring said detachable connection, said first pedal can be locked in depressed position by said swinging arm, but when they are limited to the other locus of vibration no such locking action can occur.

14. A combination such as defined in claim 13 in which said adjustable means for limiting the locus of vibration of said arm and second pedal comprises a stationary shaft, a rotatable sleeve to which said arm and pedal are rigidly connected mounted on said shaft and having a projecting jaw at one end, a collar mounted on said shaft and

having a projection in the plane of rotation of said jaw, and clamping means for holding said collar in different positions of circumferential adjustment on said shaft.

15. A combination such as defined in claim 13 in which said adjustable means for limiting the locus of vibration of said arm and second pedal comprises a stationary shaft, a rotatable sleeve to which said arm and pedal are rigidly connected mounted on said shaft and having a projecting jaw at one end, a collar mounted on said shaft and having a projection in the plane of rotation of said jaw, and clamping means for holding said collar in different positions of circumferential adjustment on said shaft together with a pin set in said shaft and projecting through a cutaway portion of said collar.

16. In a multiple pedal system for controlling the operation of an addressing machine, adapted to operate with a series of stencil cards, which said system comprises a pedal adapted when depressed to cause the machine to print from said cards, and a second pedal adapted when depressed to cause the machine to skip said cards, means whereby a depression of said skip pedal also depresses said printing pedal, and an automatically controlled lock for holding said skip pedal in depressed position, the combination, with said above described apparatus, of means for temporarily disabling said lock.

17. A combination such as defined in claim 16 in which said lock comprises a swinging arm having a limited angle of swinging movement, and said disabling means comprises a device for shifting the locus of the angle through which said arm may swing.

18. The combination, with power-driven mechanism, of a power disconnecting device normally tending to become operative, a pedal, connections from said pedal to said device normally serving to hold the latter inoperative while said pedal is depressed, a second pedal and means whereby the depression thereof will cause simultaneous depression of the first mentioned pedal, a lock for said second pedal adapted, when in normal operation, to temporarily hold it in depressed position, and means for temporarily completely disabling said lock so that no locking action whatever can occur during such period of disablement.

19. The combination, with power-driven mechanism, of a power disconnecting device normally tending to become operative, a pedal, connections from said pedal to said device normally serving to hold the latter inoperative while said pedal is depressed, a second pedal and means whereby the depression thereof will cause simultaneous depression of the first mentioned pedal, a lock for holding said second pedal in depressed

position, automatic means for breaking said connections while said first mentioned pedal is depressed, apparatus under control of the operator for restoring said connections when said pedals are in raised position, and means for temporarily disabling said lock.

20. The combination, with power-driven mechanism, of a power disconnecting device normally tending to become operative, a ¹⁰ pedal, connections from said pedal to said device normally serving to hold the latter inoperative while said pedal is depressed, a second pedal and means whereby the depression thereof will cause simultaneous de-

pression of the first mentioned pedal, a lock ¹⁵ for holding said second pedal in depressed position, automatic means for breaking said connections while said first mentioned pedal is depressed, apparatus under control of the operator for tripping said lock and re- ²⁰ storing said connections when the pedals have been so released, and means for temporarily disabling said lock without disabling said connection restoring means.
